UNITED STATES PATENT OFFICE.

CHARLES D. SMITH, OF MORGANTOWN, WEST VIRGINIA, ASSIGNOR OF ONE-HALF TO MICHAEL G. WEBB, OF BALTIMORE, MARYLAND.

GARMENT-FASTENER.

No. 926,614.

Specification of Letters Patent.

Patented June 29, 1909.

Application filed June 5, 1908. Serial No. 436,948.

To all whom it may concern:

Be it known that I, CHARLES D. SMITH, a citizen of the United States, residing at Morgantown, in the county of Monongalia and State of West Virginia, have invented new and useful Improvements in Garment-Fasteners, of which the following is a specification.

This invention relates to closures and fasteners for the meeting edges of garments, such as corsets, gloves, leggings, shoes and other like articles of that character having portions adapted to be fastened together to close or secure the device about the part of 15 the person to which it is to be applied.

The object of the invention is to provide a closure and fastener of that type embodying a tongue or strip to engage and close the space between the meeting edges, and to provide a means whereby the tongue may be quickly applied and removed so that the garment may be practically instantaneously fastened and unfastened.

The invention consists of the features of 25 construction, combination and arrangement of parts hereinafter fully described and claimed, reference being had to the accompanying drawing, in which:—

Figure 1 is a fragmentary front elevation 30 of a shoe upper showing the application of the invention to close the opening in the front of the upper. Fig. 2 is a cross section on line 2—2 of Fig. 1. Fig. 3 is a longitudinal section on line 3—3 of Fig. 1. Fig. 4 is a 35 front view of the tongue or closure strip. Fig. 5 is a perspective view of one of the guide tips. Fig. 6 is a similar view of one of the guide tubes. Fig. 7 is an inner side view of one of the caps of the handle.

Referring to the drawings, the numerals 1 and 2 designate the meeting edges of a garment, such, for instance, as the divided portion of the upper 3 of a shoe. The marginal portions of these edges are inturned to form 45 reinforcing pockets or folds 4 receiving the heads of a series of rivets or fastening devices 5. The series of rivets or fastening devices upon each meeting edge carry a series of guide tubes 6, which are suitably spaced apart to prevent impairment of the flexibility 50 of the material of the garment to an objectionable degree. The outer side of each guide tube is formed with a longitudinal slot 7 and the edges 8 thereof are turned outwardly to 55 impart a flaring formation to said slot.

The space between the meeting edges is adapted to be closed by a covering strip or tongue 10, made of any suitable flexible material. The longitudinal side edges of this tongue are rolled to form guides 11 to slidably engage the opposite series of guide tubes upon the meeting edges 1 and 2, the lower ends of said rolled edges terminating above the lower end of the tongue, leaving the latter free to project in the form of a tab 12 60 below the meeting edges, when the tongue is applied, said tab serving as a finger piece by which the tongue may be drawn downward into position and adjusted as tightly as desired. The rolled edges 11 may be reinforced 65 by a strengthening core 13 of flexible wire or other suitable material. In practice, the tongue may be slightly tapered longitudinally; so that in the process of drawing it downward through the guides the meeting 70 edges will be gradually drawn together and the tongue retained securely in position through the frictional engagement between said rolled edges and the guide tubes. It will be understood that the rolled edges are 75 of proper diameter to snugly, yet easily fit said tube, and that the slots 7 in the tube permit of the passage of the strip from one set of tubes to the other.

The upper ends of the rolled or beaded 80 edges 2 are provided with guide tips or caps 14, the lower ends of which are tubular in form to receive and fit over the upper ends of the beads and are fastened thereto by pins or other suitable securing devices 15. The 85 upper ends of the tips or caps are of conical form as indicated at 16, and from the body of each tip or cap projects a slotted lateral extension 17, which receives and engages the adjacent portion of the upper edge of the 90 tongue to add to the security of the connection. The sides of this slotted or bifurcated connection are formed with registering openings 18 which coincide with corresponding 95 openings in the material of which the tongue is made.

It will be seen from the foregoing description that by simply fitting the lower ends of the guide beads into the upper guide tubes and drawing the tongue downward through 100 the medium of the tabs 12, the beads will slide through the guides and thus the tongue may be brought into position to cover the space or opening between the meeting edges 1 and 2 and to draw said meeting edges to- 105 110

gether, the construction and arrangement of the guide tubes and parts insuring ample flexibility of the garment in use. The tongue is designed to be removed by an upward 5 sliding movement, so that the meeting edges may be connected or disconnected in a practically instantaneous manner.

In order to facilitate the removal of the tongue, a handle or detachable removing device therefor is provided. This device comprises a pair of members 19 in the form of tubes or caps adapted to engage the upper conical ends of the tips. Projecting from these tubes or caps are rigid arms 20 having hooked ends 21 to engage the openings 18 in the parts 17, the two arms being connected by a loop handle or grip 22, preferably made of some suitable flexible material, so that the handle when detached from the tongue 20 may be conveniently collapsed in close compass and carried in the pocket. When it is desired to detach the tongue, the hooks of the arms are engaged with the openings in the extensions of the tips and the tubes or 25 retaining devices 19 fitted in position upon the ends of the tips, by which the arms are held in place, and then the handle or grip 22 is grasped and an up pull exerted, whereby

the tongue may be drawn upwardly, its beaded edges 11 sliding in the guide tubes, 30 so that it may be removed in a convenient and expeditious manner.

Having thus fully described the invention, what is claimed as new is:

1. A detachable handle for tongues of the character described, comprising a pair of socketed retaining devices, engaging devices projecting therefrom and having hooked free ends, and a cord or like flexible connection between the said sets of devices. 35

2. A detachable handle for tongues of the character described, comprising a pair of retaining devices having engaging members projecting therefrom, and a flexible connection between said retaining devices. 40

3. A detachable handle for tongues of the character described, comprising socketed retaining devices having hooked engaging members projecting therefrom, and a flexible connection between said devices. 45

In testimony whereof I affix my signature in presence of two witnesses.

CHARLES D. SMITH.
